SAFETY DEVICE FOR ACCESSORY APPARATUS ON RAILWAY TRAINS

Filed Nov. 8, 1946

UNITED STATES PATENT OFFICE

2,584,234

SAFETY DEVICE FOR ACCESSORY APPARATUS ON RAILWAY TRAINS

Lewis K. Silcox, Watertown, N. Y., assignor to
 The New York Air Brake Company, a corporation of New Jersey

Application November 8, 1946, Serial No. 708,535

1 Claim. (Cl. 246—169)

1 This invention relates to protective devices for assuring a safe condition of accessory devices on railway trains on approach to particular portions of the track. The result is effected by interlocking the accessory device with a train control device which normally responds to trackside signals controlling train movement.

To bring about the desired result the interlock is between the accessory device and the acknowledging or forestalling device (forming part of most train control systems) which permits the engineer to pass a signal set against him, provided he operates the acknowledging device at the proper time. The interlock is such that if the accessory device is in an unsafe condition operation of the acknowledging device is inhibited. To compel operation of the forestalling device a special trackside element is installed at the desired point on the track. This is an independent unit not related to the trackside signal system which controls train movement.

As an important and typical embodiment of the invention it will be described as embodied to ensure that a locomotive leaving a water pan carries its water scoop in completely retracted position.

The water pan extends between the track rails for several hundred yards and ends in a cam or ramp designed to ensure that the scoop will rise over the leaving end of the pan in the event that the engineer is slow in operating the control. The scoop is hinged to the tender and may be lowered by the engineer so that its leading end dips into water in the pan and conducts water up into the tank in the tender by an inertia reaction. The engineer is supposed to retract the scoop when the tank is filled, and in any event before the leaving end of the pan is reached. The scoop is motor actuated, and failure to lift the scoop to its fully retracted position can occur as the result of some mechanical failure, without fault of the engineer, and without knowledge by the engineer that such failure has occurred.

To guard against accident in the event of such a failure or of negligent manipulation, the invention contemplates disabling the acknowledging device except when the scoop is fully retracted. A trackside unit compels acknowledgement as the locomotive leaves the pan and, in the case of a water scoop installation, would be set always to actuate the train control.

This last condition is not indispensable for all installations; because certain accessory devices might require checking only at certain times.

2 Most train control systems include a timing device designed to prevent abuse of the acknowledging device. For example, one here illustrated allows the acknowledging device to be effective for fifteen seconds, so that the engineer can acknowledge as he approaches the signal. With such an arrangement the trackside unit may be located a short distance beyond the leaving end of the pan, so that the engineer will have time to acknowledge after the latest practicable retraction of the scoop.

While the principle could be explained by simple diagrams, a commercial installation is illustrated in the drawing. This involves, merely by way of example, a known water scoop mechanism with a dual limit switch attached and interposed in the acknowledging circuits of the General Railway Signal Company's Intermittent Train Control.

To render an extremely detailed description of this well known commercial train control system unnecessary, there are filed with this application the following publications:

G. R. S. Automatic Train Control, Intermittent Inductive Auto-Manual System. Handbook No. 6, second edition (copyright 1928) and Pamphlet B-526, third edition (copyright 1926).

The circuit diagram in applicant's drawing is based on Fig. 32 of Handbook No. 6 and Fig. 9 of Pamphlet B-526. The same diagram appears in each and the reference letters and numbers are used on the application drawing.

In the drawings:

Fig. 1 shows portions of a locomotive tender with the waterscoop in elevation in its lowered position. The train control circuits are shown in diagram.

Fig. 2 is a view similar to a portion of Fig. 1 but showing the water scoop in its normal, raised position.

Fig. 3 is a plan view of the track, drawn on a small scale, and indicating an acceptable arrangement of the end of the water tank (with its ramp) and the trackside element used according to the invention.

Referring first to Fig. 1 a track rail is indicated at 11, a tender wheel at 12 and a portion of the tender underframe at 13. Hung from the underframe 13 is the bracket 14 which supports the fulcrum 15 of a three-armed lever, one of whose arms 16 is connected by link 17 with the piston rod of a double-acting air motor generally indicated by the numeral 18 applied to its cylinder. A control valve 20 is provided to enable

the engineer to operate this motor full stroke in either direction as desired.

A second arm 19 of the three-armed lever swings between stops 21 and 22 sustained by the frame 13. Arm 19 is connected by link 23 and chain 24, respectively, to two articulated hollow sections 25 and 26 of the water scoop. Section 26 is hinged to the hollow bracket 27, through which scooped water is delivered to the water tank (not shown).

A third arm 28 of the three-armed lever reacts upward in a counter-balancing spring assembly generally indicated at 29. This is sustained by a pad 31 carried by the underframe 13. The spring assembly biases the three-armed lever to the position shown in Fig. 2 in which the water scoop is raised. In that position the open end of the scoop is protected by a shield 32 sustained by the brackets which carry stop 21.

The mechanism so far described will be recognized as a commercial form of water scoop. It coacts with a water pan 33 arranged between two track rails 11 as shown in Fig. 3. A cam rail or ramp 34 is located at the leaving end of pan 33 to lift the scoop over the end of the pan if the engineer is late in retracting it.

Mounted above stop 22 is the housing 35 of a limit switch which produces the interlock with the acknowledging or forestalling circuit to be described. Guided in the housing is a plunger or stem 36 urged downward by a coil compression spring 37. When the plunger is at its lower limit of motion its lower tip projects beyond stop 22 in position to be forced up by arm 19 as the arm closely approaches stop 22. The stem carries two contactors 38, 39 which bridge corresponding pairs of bow contacts only when the stem is forced up by arm 19. Thus the limit switch is in effect two switches operated in unison. Each controls a corresponding part of the acknowledging (forestalling) circuit in such a way that the circuit is interrupted unless arm 19 is against stop 22, at which time the scoop is fully retracted (see Fig. 2).

A typical train control circuit capable of control by a limit switch such as 35 is diagrammed in Fig. 1, is fully described in the publications mentioned, and being familiar to persons skilled in the art, will be only briefly described.

The three relays R1, R2 and R3, as well as the electro-pneumatic valve E. P. V., are energized from the headlight generator G. The circuit through the electro-pneumatic valve from the generator is wire B32, contact 3 of relay R2, wire P3, contact 6 or 7 of relay R3, wire P2, contact 8 of the reset contactor, contact Z, wire P4A, the electro-pneumatic valve and wire C to the generator. Relay R1 is energized through wire B32, contact 3, wire P3, contact 6 or 7, wire P2, contact 1, wire S1, the secondary coil S of the receiver, the coil of relay R1, the ballast lamps LL and primary coil P of the receiver to wire C. Relay R2 is energized through wire B32, contact 3, wire P3, contact 6 or 7, wire P2, contact 2 and coil R2 to wire C. Relay R3 is energized through wire B32, contact 3, wire P3, contact 6 or 7, wire P2, relay coil R3, the ballast lamps LL, the primary coil P of the receiver and wire C.

When the receiver passes over an open circuited trackside inductor such as 41 (Fig. 3), an electromotive force is momentarily induced in the coil S and of opposite polarity to that of the generator. This results in a sudden drop in voltage and current flow at relay R1 and contacts 1 and 2 open. Since the circuit of relay

R1 was made through contact 1, this relay is not reenergized after the inductor is passed. The relay R2 is also deenergized when contact 2 opens; this in turn causes contact 3 to open and contacts 4 and 5 to close. The opening of contact 3 causes relay R3 to be deenergized, and its contacts 6 and 7 will open; this results in the electro-pneumatic valve being deenergized to produce a brake application.

In order to prevent a brake application the engineman must move the handle of the acknowledging contactor to closed position before the receiver passes over the wayside element. In this position contacts X and Y are closed and a circuit is completed through wire B32, the whistle valve WV, contact X, contact 6 or 7, wire P2, coil of relay R3, ballast lamps LL, primary P of the receiver, and wire C. This forms a circuit through the coil of relay R3 by-passing the contacts of relays R1 and R2. With relay R3 energized, the electro-pneumatic valve will remain energized and no brake application occurs.

According to the invention the limit switch 35 is interposed so that one of its contactors 39 controls the circuit also controlled by the switch X, and the other of its contacts 38 controls the circuit also controlled by the switch Y. Thus, neither of the switches X or Y can complete its circuit unless the water scoop is so fully retracted that the switch 35 is in the circuit closing position of Fig. 2.

The train control circuit is customarily located on the locomotive and the water scoop is customarily located on the tender. Therefore, the interlocking circuits must lead to the tender. Jumpers, indicated generally at 42, are provided between the locomotive and tender.

Operation

Suppose that the engine has taken water from the pan 33. As the engineer approaches the leaving end of the pan he operates the control for the motor 18 to retract the water scoop, and then operates the acknowledging or forestalling switches XY. If the scoop is all the way up in the position of Fig. 2, the forestalling switches X and Y will be operative because the switch 35 will be closed. Consequently, when the locomotive passes the trackside inductor 41 the train control device will not be operated and no brake application will be produced.

However, if the water scoop is not completely retracted so that the switch 35 is open, neither of the two forestalling switches X or Y can complete the forestalling circuit. Consequently, the train control will operate and produce a brake application. This will stop the train and warn the engineer that the water scoop apparatus has not functioned properly.

Since this protection is desirable at all times the trackside unit 41 can be a simple bar of soft iron without any choke coil such as that customarily used with trackside elements in the G. R. S. system.

In any case where the protective feature would be needed at certain times and not at others the conventional trackside element with choke coil and some controlling mechanism therefor be used.

As is well understood the acknowledging contactor of the G. R. S. system cannot be held closed for more than fifteen seconds because a clockwork arrangement forming part of the control will open the switch Z after the acknowledg-

ing contactors have been closed for the period stated.

This provision is for the purpose of permitting the engineer to acknowledge a signal as he approaches it without permitting abuse of the acknowledging mechanism. Because of this arrangement it is advisable to locate the trackside inductor 41 a short distance beyond the leaving end of the pan 33 so that if the engineer lifts the scoop just before he leaves the end of the pan he will still have time to acknowledge the trackside unit 41.

As suggested, an interlocking switch 35 or its equivalent could be arranged to be operated by any train carried piece of accessory apparatus which has a safe position and is potentially dangerous unless it is in that position. Furthermore, the function of the switch 35 is to disable the acknowledging mechanism, whatever that may be.

By interposing the interlock between the accessory device and the acknowledging device it is possible to avoid any change in, or interference with, the normal functions of the train control.

Obviously, therefore, the invention is applicable to a wide range of accessory apparatus, and to specifically different types of train control, in lieu of the particular pieces of apparatus here described to illustrate the broad principles of the invention.

What is claimed is:

The combination of a railway track; a rail vehicle which runs thereon; an automatic control system including signal-set trackside elements, coactive vehicle-carried elements, normally responsive thereto to stop the vehicle, and a vehicle-carried acknowledging device which

when actuated serves to prevent vehicle-stopping response of said system; a vehicle-carried accessory device having a safe position and at least one potentially dangerous position; a controller adapted to be manually set by the operator of the vehicle alternatively in two positions, in one of which it causes said device to move to, and in the other of which it causes said device to move from said safe position; means actuated by said accessory device and effective in all positions thereof except said safe position to suspend the functioning of said acknowledging device; and a trackside element located near a point on the track at which the operator should shift said controller to cause said device to move to safe position, said trackside element being continuously conditioned to actuate the vehicle-carried elements of the control system.
